UNITED STATES PATENT OFFICE.

EDWARD WALDER, OF KANSAS CITY, MISSOURI.

ELECTRIC HEATER.

1,377,037.

Specification of Letters Patent.

Patented May 3, 1921.

Application filed August 26, 1920. Serial No. 406,109.

To all whom it may concern:

Be it known that I, EDWARD WALDER, citizen of the United States, and resident of Kansas City, county of Wyandotte, State 5 of Missouri, have invented a certain new and useful Improvement in Electric Heaters, of which the following is a complete specification.

This invention relates to electric heaters 10 of that general class comprising a cement body in which provision is made for air to enter at the bottom and escape at the top, resistance coils located within the body in the path of such air to heat the same as it passes 15 upwardly, and my object is to produce a heater of this character which will operate efficiently, which is susceptible of being knocked down for convenience of portability, and which is of simple, strong, durable 20 and inexpensive construction.

With this object in view, the invention consists of certain novel and useful features of construction and the combination of parts as hereinafter described and claimed; and in 25 order that it may be fully understood, reference is to be had to the accompanying drawing, in which:—

Figure 1 is a central vertical section of an 30 electric heater embodying the invention.

Fig. 2 is a central vertical section of the 35 heater taken at right angles to the section disclosed by Fig. 1.

Fig. 3 is a top plan view of the heater 40 with the cover omitted.

Fig. 4 is an inverted plan view of the 45 heater.

Fig. 5 is a fragmentary elevation of the 50 heater with the hollow body portion omitted.

In the said drawing, the base or supporting 55 part of the heater comprises a pair of inverted U-shaped brackets 1 and 2 arranged cross-wise with respect to each other and fastened together at the crossing point by a rivet 3.

Mounted upon the base or support is a 60 circular concrete block 4, which in diameter is smaller than the span of the brackets 1, and said block is provided with an elongated opening 5 extending from the top to the bottom and with a groove 6 semi-cylindrical in form which extends from the opening 5 to the periphery of the block.

A block of similar contour and diameter 65 but of greater depth is indicated at 7 and rests upon the block 4, and is provided with an elongated opening 8 registering with and

forming a continuation of the opening 5 of block 4. In the lower edge or end of block 7 is provided a semi-circular groove 9 extending from the opening 8 to the periphery 60 of the block and registering with the opening 6 and forming in conjunction therewith a circular or cylindrical opening wherein is fitted a socket 10 for engagement by a cord 65 plug, (not shown).

To secure the circular blocks 4 and 7 rigidly together and yet provide for their separation when necessary, bolts 11 extend through one of the brackets 2 and up through said blocks and are engaged at their 70 upper ends by washers 12 and clamping nuts 13, the latter serving to clamp the washers firmly down upon the block 7.

Arranged vertically within the passage 75 formed by the registering openings 5 and 8 is a pair of tubes 14 of porcelain or the like, susceptible of being highly heated without fracturing, and said tubes at their lower ends are enlarged to form upwardly facing shoulders 15. The tubes respectively rest 80 upon U-shaped retainers 16 of wire, the connection being made secure by overlapping the upper ends of the legs of said retainers on the said shoulders 15. The retainers rest upon the brackets 2 and at their centers are 85 formed with eyes 17 through which headed screws 18 extend, said screws also extending through said bracket 2 and being secured in position by clamping nuts 19 engaging their threaded ends. 90

Secured upon the tubes 14 respectively are clamping bands 20, forming rests for coiled wires 21 inclosing said tubes respectively for the greater part of their length, the lower terminals of said coils which are 95 resistance coils, being connected as at 22 to the socket 10 in the usual or any preferred manner, the upper ends of the coils being detachably connected by a link 23.

A cylindrical hollow body portion 24 of 100 concrete or the like is fitted over the blocks 4 and 7 and rests upon the base or support and is provided at its upper end with a series of exit openings 25 which slope downwardly and outwardly for the purpose of 105 directing the hot air downwardly toward the floor of the room in which the heater is located. The cylinder is provided with a cover 6 of concrete or the like, the said cover depending slightly within the body to 110 guard against accidental dislodgment.

A heater of this character is adapted to

be connected by a cord and plug (not shown) with a wall socket or the like, and within a very short time the resistance coils raise the insulating tubes to a high temperature, the high temperature developed resulting in a circulation of air up through the passage composed of openings 5 and 8 and the interior of the tubes 14, this air escaping downwardly and outwardly 10 through the exit openings 25.

A heater of the type described is not only efficient in operation, but it minimizes danger of fire and is of such weight that it cannot readily be knocked over, the making 15 of it in sections permitting it to be handled readily by a single attendant so that it can be set up at any desired point with ease and convenience.

From the above description, it will be apparent that I have produced an electric heater embodying the features of advantage set forth as desirable in the statement of the object of the invention, and which may be modified in minor particulars without departing 25 from the spirit and scope of the appended claims.

I claim:

1. A heater comprising a skeleton base, a cement block resting upon the base and provided with an opening, a second cement block superimposed upon the first and provided with a registering opening, a plurality of tubes extending vertically through the passage formed by said registering openings, means for fastening said tubes to the said base, resistance coils encircling said tubes and connected together to transmit electric current from one of the coils to the other, a hollow cylindrical body inclosing 35 said block and resting on said base and provided in a plane above that of the block with exit openings, and a cover closing the upper end of said body.

2. An electric heater comprising a skeleton base, a concrete or cement block resting on the base and provided with a vertical opening, a second concrete block resting upon the first and provided with a vertical opening registering with the opening of said 45 first block, a plurality of tubes extending said opening and provided at their lower ends with upwardly facing shoulders, U-

shaped retainers interposed between said tubes and said base and interlocked with said shoulders to prevent upward movement 55 of said tubes, beams fastening said retainers to said base, resistance coils inclosing said tubes and connected together in series, a hollow body fitting over said block and resting on said base and provided at its upper 60 end with exit openings, and a cover for said body.

3. A heater comprising a skeleton base, a cement block resting upon the base and provided with an opening, a second cement block superimposed upon the first and provided with a registering opening, a plurality of tubes extending vertically through the passage formed by said registering openings, means for fastening said tubes to the 70 said base, resistance coils encircling said tubes and connected together to transmit electric current from one of the coils to the other, a hollow cylindrical body inclosing said block and resting on said base and provided in a plane above that of the block with exit openings, and a cover closing the 75 upper end of said body and fastening devices extending up through said base and said superposed block.

4. A heater comprising a skeleton base, a cement block resting upon the base and provided with an opening, a second cement block superimposed upon the first and provided with a registering opening, a plurality of tubes extending vertically through the passage formed by said registering openings, means for fastening said tubes to the said base, resistance coils encircling said tubes and connected together to transmit 85 electric current from one of the coils to the other, a hollow cylindrical body inclosing said block and resting on said base and provided in a plane above that of the block with exit openings, and a cover closing the 90 upper end of said body; the juxtaposed faces of said blocks having grooves conjointly forming openings extending from the periphery of said blocks to the openings thereof, and an electric socket connected to the lower end of said coil.

In testimony whereof, I hereto affix my signature.

EDWARD WALDER.
